(57) **CLAIM**

I claim the ornamental design for a magnetic engine oil drain plug, as shown and described.

DESCRIPTION

FIG. 1 is a top perspective view of the magnetic engine oil drain plug;

FIG. 2 is a bottom perspective view of the magnetic engine oil drain plug;

FIG. 3 is a first side view of the magnetic engine oil drain plug;

FIG. 4 is a second side view of the magnetic engine oil drain plug;

FIG. 5 is a top view of the magnetic engine oil drain plug; and,

FIG. 6 is a bottom view of the magnetic engine oil drain plug.

The broken lines in the drawings depict parts of the article that form not part of the claimed design.
